HOT TOP

Ernest J. Turner and William A. Turner, Pittsburgh, Pa., assignors to McLain Fire Brick Company, Pittsburgh, Pa., a corporation of Delaware

Application February 6, 1934, Serial No. 709,956

1 Claim. (Cl. 22—147)

The present invention relates to an improvement in hot tops; and more particularly to an improvement in the hot top shown in the Patent to Turner 1,593,518.

5 The hot top shown therein has proved advantageous in operation in that the same functions more efficiently in affording a reservoir of metal which flows into the body of the ingot during solidification of the mass of metal therein. The 10 portion of the metal confined within the hot top which is available to thus flow into the body of the solidifying ingot depends to a large extent upon the insulating properties of the hot top. The hot top disclosed in said patent operates so 15 efficiently to provide a reservoir of molten metal that the required volume within the hot top may be decreased an appreciable amount, thus reducing the amount of metal which must be discarded.

We propose to improve the insulating properties of the hot top by heating up the refractory material of which the hot top is formed before the ingot is completely poured. During the pouring operation, molten metal enters the ingot mold at a temperature upwards of 2900°. Of course, 20 the metal entering the mold displaces air which must flow upwardly out of the mold; and during its upward passage this air attains a high temperature. We propose to extend the openings in the side walls of the hot top so as to permit flow of hot 25 gases vertically through these side walls. The thickness of refractory material surrounding these vertical passageways is small enough so that by the time the ingot is poured and the hot top is filled with molten metal, the refractory material 30 has been preheated by the upwardly rising air to a high temperature. At this time the molten metal reaching the lower ends of the passageways freezes therein and seals the same so that the side walls which are now at a high 35 temperature prevent the dissipation of the heat of the reservoir of molten metal within the hot top, the insulating effect being aided by the air spaces formed in the side walls.

The conservation of the heat in this molten 40 metal in the hot top is aided by using a top wall or lid shading or sheltering the marginal portions of the top of the mass of metal confined within the hot top. The extent of such protection is obviously determined by the size of pouring opening which must be provided in the lid.

In the accompanying drawing which illustrates our invention,

Fig. 1 is a plan view of a hot top with lid, the side walls being formed with vertical passages therethrough;

Fig. 2 is a side view partially broken away on the line II—II of Fig. 1 of the hot top shown in that figure, the top of the ingot mold being shown in chain lines;

Fig. 3 is a view similar to Fig. 1 showing a hot top without lid;

Fig. 4 is a view similar to Fig. 2 showing the form of hot top of Fig. 3 and partially broken away on the line IV—IV of Fig. 3.

The composition of material determined upon for use in manufacturing the hot top may be formed into suitable shape by molding, extrusion, or the like. The hot top is formed with side walls 6 having vertical passages therethrough. This is readily accomplished by providing compound 15 walls comprising an inner shell 8 and an outer shell 9 connected by relatively narrow ribs or webs 10. The above mentioned vertical passages 12 extend through the side walls 6 from bottom to top, and are adapted to permit flow of hot gases 20 upwardly through the walls of the hot top as the molten metal is poured into the ingot mold 13.

In the form of hot top shown in Figs. 1 and 2 a marginal top wall or lid 15 surmounts the side walls 6, the lid 15 terminating short of the outer 25 shell 9 so as to afford free passage for gases rising through the passages 12. In the embodiment shown in the drawing the borders of the lid are restricted so as not to overlie the passages 12. The lid should be so arranged that its edge portions are in spaced relation to the outer side wall or shell 9; and accordingly these edge portions of the lid should be upturned if they extend outwardly in an appreciable amount over the passages 12. The lid 15 is provided with a 30 pouring opening 16 such as is required to admit the stream of molten metal. In the form of hot tops shown in Figs. 3 and 4, the lid 15 is omitted.

The hot top may be positioned in the desired 40 relation to the top of the ingot in any suitable fashion. In the form of hot top shown in Fig. 2 we have provided the same with cut-outs 18; and the hot top is blocked up at the desired level by blocks 19 resting on the top of the ingot mold 13 and having their upper inner edges entered in the cut-outs 18. In the form of hot top shown in Figs. 3 and 4, ribs 20 integral with the side wall of the hot top are formed in the course of manufacture of the hot top; and these ribs engage blocks 21 of suitable thickness which are supported by the top of the ingot mold 13. It will thus be understood that the means for supporting the hot top may comprise lugs, ribs, cut-outs or any other convenient type of support.

The advantages of the present invention arise 50

in part from the higher temperature at which it is possible to maintain the mass of metal in the hot top during the time that solidification is taking place within the ingot mold proper.

5 While we have illustrated and described certain preferred forms of our invention it will be understood that the contour, composition and other incidents to the formation of the hot top may be modified; and that accordingly the invention may be otherwise embodied and practiced within the scope of the following claim.

We claim:

As an article of manufacture, an ingot mold hot top formed with compound side walls comprising inner and outer shells of refractory material connected by ribs or webs providing air spaces therebetween which spaces are open at both the top and the bottom, and a lid integral with the top of the inner shell, said lid having a central pouring opening and terminating in spaced relation to the outer shell to leave open the tops of said air spaces. 10
